UNITED STATES PATENT OFFICE

2,444,992

PORTABLE DEVICE FOR AIRPLANE
LANDING WHEELSHoward S. Kittel, Fort Worth, Tex., assignor to
Consolidated Vultee Aircraft Corporation, San
Diego, Calif., a corporation of Delaware

Application November 20, 1943, Serial No. 511,027

9 Claims. (Cl. 214—1)

1

This invention relates to a wheel positioner and is more particularly described as a portable lifting and handling device for readily mounting and dismounting airplane landing wheels.

An important object of the invention is to provide a wheel and tire engaging apparatus for raising, moving and tilting wheel assemblies as now used for large trucks, airplanes, and the like, to move the wheels to and from the storage position and to facilitate the mounting of the wheels upon an aeroplane and to dismount them therefrom.

A further object of the invention is to provide a portable carrier in which a large tire or wheel assembly is mounted for turning from a horizontal to an upright position with apparatus for raising or lowering the wheel in either position.

A still further object of the invention is to provide a portable wheel positioner in which the frame is formed of hollow tubing so that lifting cables may be generally concealed and enclosed thereby to provide a neat assembly and to prevent the danger of contact of the cables with the hands or clothing of an operator.

Another object of the invention is to provide a portable wheel positioner which is generally of new and improved construction and is characterized by simplicity of design as well as ease or facility of assembly.

Other objects of the invention and various advantages and characteristics of the present portable wheel handling device will be apparent from a consideration of the following detail description.

The invention consists in the several novel features which are hereinafter described and more particularly defined by claims at the conclusion hereof.

In the drawings which accompany and form a part of this specification or disclosure, and in which like letters and numerals of reference denote corresponding parts throughout the several features;

Figure 1 is a perspective of a portable device for handling airplane landing wheels in accordance with this invention with the wheel holding structure in a horizontal position;

Figure 2 is a front elevational view of the structure shown in Figure 1 with a wheel holding structure including a wheel assembly in vertical position;

Figure 3 is a sectional detail of the frame and lifting structure;

Figure 4 is a sectional view illustrating portions of the raising and lifting mechanism;

Figure 5 is a sectional view illustrating portions of the lifting mechanism;

Figure 6 is a detail sectional view of the lifting structure at the pivotal mounting; and

2

Figure 7 is a perspective of the pivotal mounting.

In the development of large trucks and airplanes, the sizes of their landing wheel assemblies are so large, the wheels in many cases attaining such huge dimensions and such heavy weights that a troublesome problem is presented in the handling thereof. Complications arise both in the movement of the wheels to and from storage, and in applying the wheels to and dismounting them from their axles, struts, and other supports. The present invention provides an improved form of portable lifting device which is operative to effect the ready movement of a large wheel assembly, and simplifies the task of mounting and dismounting a tire or a wheel. In carrying out the invention, a tire gripping or holding assembly engages and supports a tire or wheel and is pivotally mounted in a movable supporting frame where it is mounted for raising and lowering movement.

Referring now more particularly to the drawings, a movable supporting platform 10 comprises a tubular member 11 bent substantially to a U-shape form of a size to embrace a tire or wheel to which it is applied. Swivel casters 12 are positioned one at the outer ends of each of the extremities and a third upon a projection 13 extending outwardly from the rounded central portion for supporting the frame.

Two tubular posts 14 and 15 are secured in upright position near the outer ends of the tubular member 11 connecting with the interior thereof and are additionally supported by metal plates 16 welded or otherwise attached to the lower ends of the posts and the adjacent portion of the frame. A third upright tubular post 17 is mounted at the top of the rounded portion of the frame member 11 and communicates at the bottom with the interior thereof, the post being supported by three short angular braces 18 extending to the sides of the frame member and rearwardly to the projection 13.

Slidably movable upon each of the side posts 14 and 15 is a short sleeve section 20 to which is attached a projection 21 having a pivot perforation 22 in a downwardly extending portion and a perforated bracket 23 extending upwardly therefrom. A trunnion pin 24 having a collar 25 is inserted from the inner side of the projection through the pivot opening 22, a washer 26 is placed upon a projecting end and a cotter pin 27 is inserted through the trunnion pin for holding it in place.

The trunnion pins 24 in opposite sides provide a support for the tire gripping or holding assembly which includes a tubular member 28 through which the outer end of each trunnion pin extends and to which they are secured, the tubular member being bent to a substantially

semi-circular form. Two opposite pick-up clips 29 are located at the ends of the tubular member 28 and an intermediate clip 30 is mounted at the inner end of the member and substantially 90° from each of the other two. The pick-up clip 30 is rigidly secured to the tubular member by welding or in any suitable manner, but the clips 29 are removably mounted at the ends thereof. Each clip 29 has opposite guideways 31 secured thereto for engaging a key-block 32 secured to the extremity of the tubular member 28 so that each of the clips 29 may be slipped inwardly at the end of the tubular member 28 at a location opposite the trunnion pin 24 for that end. To limit the extent of application of each clip 29, a stop plate 33 is welded or otherwise secured to the tubular member 28 at a distance from the end thereof to engage one of the guideways 31.

Each of the clips 29 is connected to its corresponding slideable sleeve 20 by means of a short chain section 34 attached at one end to the clip and at the other end to the sleeve so that when the clip is dismounted or removed from its engagement with the tubular member, it will not become lost or misplaced. Thus through the trunnion pins, the gripping or holding assembly is rotatably mounted upon the sleeves 20 which are slideable upon end posts 14 and 15. One end of a cable 35 is secured to the bracket 23 of each mounting sleeve 20 and extends over the pulley 36 mounted at the top of its supporting post and thence downwardly through the post over a pulley 37 at the bottom of the post and through a curved portion of tubular member 11 over pulleys 38 and 39 therein and around a pulley 40 upwardly through the tubular post 17 and over a pulley 41 at the top thereof to an operating mechanism 42 secured adjacent the top of the post. This operating mechanism comprises a drum 43 upon which the cables 35 from both sides are wound. The drum is mounted upon a shaft 44 extending to one side and having a crank handle 45 mounted thereon with a ratchet gear 46 and a spring-pressed locking pawl 47 for engaging the gear and holding it in any adjusted position.

The lifting cables 35 are thus shielded within the tubular members of the frame except at the extremities thereof which prevents them from being caught on projections during the movement of the device or fouling a workman's clothing or other objects when the lifting drum is operated. At the upper end of each of the upright posts is a cap 48 for closing the end and providing a neat appearing finished construction.

As shown in Figure 2, a tire or wheel assembly 49 is mounted in the gripping or holding assembly in vertical or upright position within the frame. In this position, the bottom of the tire rests upon the fixed holding clip 30 and the opposite sides are engaged by the clips 29. The wheel or tire is thus adapted to be applied to an axle or a wheel in a position slightly raised from the ground.

In operation, assuming the device to be empty, it is rolled by its casters 12 to a storage pile where the lifting drum is operated to move the gripping assembly vertically to the proper height through the cables 35 and the system of pulleys above described. The weight of the gripping assembly is sufficient to lower it by gravity, and in the lowering operation, the pawl 47 is released by hand. When the center line of the gripping assembly is in the same plane as the center line of the wheel assembly, in horizontal position, the lifting de-

vice is rolled toward the wheel assembly to bring the holding clips 29 and 30 into engagement with the wheel at the three points about the periphery thereof to provide a cradle therefor.

The wheel may then be raised slightly and moved away in horizontal position from other wheels with which it is stored. Then, if necessary, the wheel may be raised to bring the holding and gripping assembly to such a height that it may be rotated 90° to an upright vertical position clear of the ground as shown in Figure 2. The wheel assembly is then moved to the location of the aircraft landing gear strut, and the level of the gripping assembly is adjusted by the operation of the lifting mechanism to bring the center of the wheel or the hub of the wheel assembly into alignment with the axle of a truck or of the landing strut if it is applied to an aeroplane. The wheel positioner is then moved forward until the landing strut or axle projects through the hub of the wheel, or through the center of the tire. To free the wheel assembly from the lifting device, the gripping assembly is lowered by operating the lifting drum until the pick-up clips 29 are free from contact with the wheel. The clips may then be moved vertically away from their supporting stops 33 to disengage them from the key-blocks 32 since they are connected to their sleeves by chains 34, the clips cannot be misplaced or lost. As soon as the clips 29 are removed, the wheel positioner may then be withdrawn from the mounting axle or strut leaving the wheel in position thereon.

In removing a tire or wheel assembly from an aeroplane or other mounting axle and depositing it in horizontal position or upon a stack of other such wheels, the operation described above is substantially reversed. In moving a tire or wheel from one horizontal position to another, it is not necessary to swing it to vertical position as it will be substantially retained in the lifting device in the horizontal position and may be raised or lowered to different elevations by the lifting mechanism in this position.

Since the posts 14 and 15 are located within the swivel casters 12 at the ends of the frame, and the post 17 is within the caster mounted on the frame projection 13, the frame has great stability and does not tend to tip or overturn even under heavy load, and regardless of the position or movement of a wheel carried by the gripping assembly. This invention may be readily adapted to any type or size of landing wheels by a change in the dimensions of the gripping assembly.

The invention is not to be understood as restricted to the details set forth since these may be modified within the scope of the appended claims, without departing from the spirit and scope of the invention.

Having thus described the invention, what I claim as new and desire to secure by Letters Patent is:

1. A portable wheel handling device comprising a wheel gripping assembly adapted to embrace substantially one-half of the wheel, a U-shaped frame having upright tubular posts at the outer ends thereof, means for mounting the assembly upon pivots movably mounted upon the posts, and means carried by the frame and including flexible elements extending through the posts and connected to the pivot mountings to simultaneously move said pivot mountings to raise and lower the assembly in the frame.

2. A wheel positioning device, comprising in

combination a wheel gripping assembly having a curved member to embrace substantially one-half of the periphery of a wheel, a pair of holding clips for the ends of the member having a block and groove connection for slidably engaging each clip with the end of the member, means for limiting the insertion of the clip upon the member, and mounting means comprising pivots at the outsides of the member for raising, lowering, and turning the gripping assembly therein.

3. A wheel positioning device, comprising a wheel gripping assembly having a curved member to embrace at least one-half of the periphery of a wheel, wheel holding clips carried by the member at the ends and intermediate the ends thereof, a pivot extending outwardly at each end of the member, a supporting frame having upright posts spaced apart to receive the gripping assembly therebetween, sleeves movable vertically upon the posts and each having a mounting for engaging the pivots of the gripping assembly, and means carried by the frame and including cables extending from the tops of the posts and connected to the sleeves for raising and lowering them and the gripping assembly carried thereby.

4. A wheel positioning device, comprising a wheel gripping assembly adapted to embrace substantially one-half of a wheel from the periphery thereof and comprising pivots at the diametrically opposite extremities, a mounting frame having upright posts spaced apart to receive the gripping assembly therebetween, sleeves slideable upon the posts having bearings for engaging the pivots, the posts and frames being hollow with pulleys mounted therein to receive cables traversing each post and extending in the frame to a common position on the frame intermediate the posts, the ends of the cables being connected to the pivot mounting sleeves, and a winding drum carried by the frame to which the other ends of the cables are attached for raising and lowering the sleeves and the gripping assembly.

5. A wheel positioning device, comprising in combination a wheel gripping assembly having a curved member and removable holding clips adjacent the ends of the member to embrace substantially one-half of the wheel from the periphery thereof, a portable frame comprising a hollow curved member with upright hollow posts near the ends communicating with the interior of the frame member, mounting means movable on the posts for engaging the pivots of the gripping assembly therebetween, the extremities of the frame extending beyond the posts and having wheel casters at the ends and at a point between the ends of the frame for supporting the gripping assembly and a wheel therein at all times without overturning, an upright hollow post intermediate the ends of the frame, cables extending through the posts and the frame each connected at one end to one of the sleeves and extending from the intermediate post adjacent the top thereof, and winding means comprising a drum carried by the intermediate post and a pawl engaged crank for operating the drum to raise and lower the wheel assembly in the frame.

6. In a wheel positioning device, a hollow tubular substantially semi-circular base member, a pair of hollow vertical posts connected near the ends and communicating at the bottom with the base member, swivel casters mounted at the ends of the base member and upon a rearward extension of the base member between the ends thereof, an intermediate upright hollow post mounted

upon the base member intermediate the ends thereof and communicating with the inside of the base member, a wheel gripping assembly, and sleeves upon which it is pivoted mounted upon the two opposite posts for raising, lowering and turning movement of the wheel, a winding drum assembly mounted upon the intermediate post near the top thereof, and including a crank arm and a locking pawl and ratchet therefor, cables connected to the winding drum and each extending through the intermediate post and through the hollow base member to one of the two opposite posts and outwardly at the end of the post to engage the corresponding mounting sleeve, the posts all being mounted inwardly with respect to the swivel casters so that a wheel carried by the gripping assembly may be raised, lowered and turned from horizontal to vertical position between the posts without tipping or overturning it.

5. A wheel positioning device, comprising a wheel or tire gripping assembly adapted to engage substantially one-half of a wheel, a frame comprising a tubular curved base member and tubular vertical posts carried thereby, a winding drum assembly carried by one of the posts, slideable pivot engaging sleeves carried by two opposite posts for pivotally mounting the gripping assembly therein and raising and lowering the cables extending from the winding drum through its mounting post and through the frame and the other mounting posts to engage the sleeves slideably upon the posts.

20. 7. A wheel positioning device, comprising a wheel or tire gripping assembly adapted to engage substantially one-half of a wheel, a frame comprising a tubular curved base member and tubular vertical posts carried thereby, a winding drum assembly carried by one of the posts, slideable pivot engaging sleeves carried by two opposite posts for pivotally mounting the gripping assembly therein and raising and lowering the cables extending from the winding drum through its mounting post and through the frame and the other mounting posts to engage the sleeves slideably upon the posts.

30. 8. A portable wheel positioning device comprising, a wheeled carrier frame open at one side, upright posts at the ends of the frame at the open side and an intermediate post, an assembly including a frame having an open side and wheel or tire gripping devices at the ends of the frame at said open side, supports for said frame slideably mounted on side posts, and means including an actuating device mounted on the intermediate post and a connection between the actuating device and said supports, for raising and lowering the assembly.

35. 9. A portable wheel positioning device comprising, a wheeled carrier frame open at one side, upright posts at the ends of the frame at the open side and an intermediate post, an assembly including a frame having an open side and wheel or tire gripping devices at the ends of the frame at the open side, pivots for the ends of the assembly frame at its open side, supports for said pivots slideably mounted on side posts, and means including a windlass on the intermediate post of the carrier frame, and a cable connected to the slideable supports for simultaneously raising and lowering the assembly.

HOWARD S. KITTEL.
